US0D1000928S

(12) **United States Design Patent** (10) **Patent No.:** **US D1,000,928 S**
(45) **Date of Patent:** **** Oct. 10, 2023**

(54) **POLISHING PAD**

(71) Applicant: **Beng Youl Cho**, Seoul (KR)
(72) Inventor: **Beng Youl Cho**, Seoul (KR)
(**) Term: **15 Years**
(21) Appl. No.: **29/841,144**
(22) Filed: **Jun. 3, 2022**
(51) LOC (14) Cl. **08-05**
(52) U.S. Cl. **USPC D8/70; D8/90**
(58) **Field of Classification Search**
USPC D8/62, 70, 90; D32/40, 25; 15/126
CPC B24B 37/26; B24B 37/24; B24D 9/08;
B24D 13/14

See application file for complete search history.

Assistant Examiner — Benjamin D. Wannemacher

(74) *Attorney, Agent, or Firm* — Revolution IP, PLLC

(57) **CLAIM**

The ornamental design for a polishing pad, as shown and described.

DESCRIPTION

FIG. 1 is a perspective view of a polishing pad showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 4 Drawing Sheets
